TORQUE WRENCH

Ernest C. Worden, East Norwalk, Conn., assignor
to The Billings & Spencer Company, a corpora-
tion of Connecticut

Application September 10, 1940, Serial No. 356,201

10 Claims. (Cl. 64—29)

My invention relates to torque wrenches.

It has among its objects to provide an improved wrench of this type, and, more particularly, an improved wrench of the type described and claimed in my copending application Serial No. 351,413, filed August 4, 1940. Further objects of my invention are to provide in such a wrench an improved plural piece piston construction and also improved valve means carried by one of the parts of the piston, and improved cam means and spring means disposed in an improved relation to the parts of the improved piston, while also providing an improved casing wherein the several parts of the mechanism are enclosed. Other objects of my invention include the provision of such an improved construction whereby manufacture is substantially facilitated and whereby it is made possible to produce a wrench which will function uniformly despite variations in alignment of the parts and enabling the structure to be inexpensively produced, while also functioning satisfactorily over long periods and minimizing wear and enabling ready replacement of worn parts to be effected. These and other objects and advantages of my improved construction will, however, hereinafter more fully appear.

In the accompanying drawing, I have shown for purposes of illustration two embodiments which my invention may assume in practice.

In this drawing:

Figure 1 is a side elevation of my improved wrench in use and operated by a suitable motor driven device;

Fig. 2 is a top plan view of the wrench;

Fig. 3 is a side elevation of the same, portions of the casing being shown in section to facilitate illustration and the operating mechanism being shown in its normal position;

Fig. 4 is a central vertical section on line 4—4 of Figure 2, the operating parts being shown in their position occupied at the limit of tightening and as they are about to release;

Fig. 5 is a transverse section on line 5—5 of Figure 4;

Fig. 6 is a transverse section on line 6—6 of Figure 4;

Fig. 7 is a transverse section on the same line, but looking in the opposite direction as indicated at 7—7;

Fig. 8 is a perspective view of the main part of the piston, and

Fig. 9 is a detail view of the lower part of the operating mechanism showing a modified form of spring therein.

In this illustrative construction, I have shown

in Figure 1 my improved wrench unit, generally indicated at 1, having oppositely directed turning elements 2 and 3 on its opposite ends and respectively connected by adapters 4 and 5 to any usual electric motor operated actuator mechanism 6 and to the work, herein a bolt head or nut 7; the wrench unit 1 herein being of improved construction as hereinafter more fully described.

Referring more particularly to this unit 1, it 10 will be observed that it includes an improved casing comprising cooperating casing members 8 and 9. Of these, the member 8 forms a cylinder 10 for an improved piston, generally indicated at 11, and hereinafter more specifically described, 15 while the casing member 9 forms a cover for this cylinder while also being provided with an axial bore 12 through which the piston rod moves. As shown, the casing member 8 is also provided with a raised axial extension or projection 13 above its bottom and has a nut 14 closing a centrally disposed filling aperture 14a in the top of this extension. Herein the top of the latter is also preferably bevelled around this nut as illustrated at 15, and a rectangular, herein squared, 20 socket 16 is also provided on this extension to receive any suitable turning portion as, for example, a projecting squared end on the adapter 5. Attention here is also directed to the fact that the opposite end of the member 8 is suitably 25 internally threaded as at 17 and has the cover member 9 threaded into the same. This cover is also provided with an elongated inwardly extending and externally bevelled bearing portion 18 for the piston rod and also carries suitable 30 packing means 19 for the latter normally compressed by an externally knurled nut 20 threaded on a raised sleeve 20a in the cover. Thus, it will be observed that a vertically compact liquid tight casing is provided adapted to house a suitable 35 fluid as, for example, oil or a suitable non-freezing hydraulic brake fluid, and to be filled through the filling aperture 14a which is of sufficient diameter also to function as a vent and is conveniently disposed and accessible through the compactly disposed turning socket 16.

Disposed in this casing and cooperating therewith is the improved piston mechanism 11. This mechanism herein includes a sleeve portion 21 snugly fitting the walls of the cylinder 10 and 40 having a narrow inwardly turned annular flange 22 on its upper end. The surface of this flange 22 adjacent the bottom of the cylinder 10 also engages a coiled spring 23 acting between the bottom of the cylinder and this flange and normally 45 tending to maintain the sleeve 21 in the position

illustrated in Figure 3, while enabling this sleeve 21 to be compressed into the position shown in Figure 4. Engaging the upper face of the flange 22 is also a cooperating portion 24 of the piston 11, herein a cylindrical disc-like portion of smaller diameter than the sleeve 21 and having a flat bottom surface engaging a like flat top surface on the flange 22 and on the sleeve 21, these surfaces being preferably ground and lapped together to provide a perfect seat, herein indicated at 25. As shown, the portion 24 of the piston also has a piston rod 26 formed integral therewith and projecting therefrom in the opposite direction from the sleeve 21 and spring 23 and through the bearing 18 and packing 19 on the cover 9. Thus, it will be observed that even should the piston rod 26 be out of line with the sleeve 21 as, for example, if the cover 9 is not in exact alignment with the sleeve 21 or with the casing member 8, no difficulty is experienced since the portion 24 may locate itself as necessary eccentrically relative to the flange 22 on this sleeve without conflict with the wall of the cylinder 10. Here attention is also directed to the fact that the spring 23 acting through the flange 22 also normally acts to maintain the latter in contact with the under surface of the piston portion 24.

Cooperating with this piston is also improved oil flow controlling mechanism. Herein, the under surface of the piston portion 24 is suitably annularly recessed, as shown at 27, on diametrically opposite sides of the stem 26, and these recessed portions are provided with ports 28 in the tops thereof. These ports 28 are controlled by balls 29 in turn controlled by arcuate spring wire holding members 30 suitably fixed at one end, as at 31, to the under side of the portion 24 and having rounded cup shaped ends 32 normally pressing the balls 29 against seats on the lower ends of the ports 28. Further, it will be observed that the piston rod 26 is provided with an axial aperture 33 in its lower end opening into an axial larger chamber 34 internally threaded as at 35 and having a coiled spring 36 therein acting between a suitable abutment, hereinafter described, and a ball 37 to maintain the latter normally closing the port 33. Here it will also be observed that lateral ports 37a lead from the bottom of the chamber 34 angularly upward and communicating with the top of the cylinder 10 above the portion 24 of the piston. Herein, the spring 36 acts at its opposite end against an adjustable abutment 38 in the upper end of the chamber 34, while an outer closure or seal is provided by an outer nut 38a of larger diameter threaded into the upper end of the chamber 34. Thus, it will be observed that both the action and location of the balls and their cooperating springs are reversed as compared with my prior structure, while eliminating all need for an expensive stem type valve and utilizing an inexpensive ball valve. It is also made possible to obtain a better seat, while through utilizing wires as ball holding and seating members, any interference with the operation by pressure on the plate springs heretofore used, is eliminated. Attention is also directed to the fact that all need for a key on the locking nut is eliminated, while the seal effectually prevents leakage along the threads of the spring abutment nut herein provided.

Cooperating with the above described mechanism is also improved means for effecting rotation of the casing parts 8, 9 upon rotation of the piston rod 26 and for releasing these elements

when a predetermined torque controlled by the oil flow controlling mechanism is exceeded. Herein, these means are also of an improved construction and in an improved location. As shown, they 5 include upwardly projecting hardened cam pins 38b driven into and projecting above the piston portion 24; these pins herein being diametrically oppositely located, as illustrated, and disposed in planes at right angles to the ports 28 and also 10 having oppositely disposed inclined upper faces 39 and end abutments 40. Herein these cam members cooperate with cooperating hardened cam members 41 of similar shape and having similar sloping faces 42 and abutments 43 but 15 depending at spaced points around and formed integral with an upper cam carrying ring member 44. Herein this member 44 is also provided with a central beveled aperture 45 adapted to receive the beveled bearing 18, while being maintained spaced from the latter due to engagement 20 of the cover 9 with the top of the ring 44. Further, it will be observed that the ring 44 is suitably attached, as by suitable screws 46 extending through the side walls of the upper end of the casing member 8 below the threads 17 thereon 25 into which the cover 9 is threaded, while cooperating annular sealing shoulders 47 are also provided on this ring and the casing 8 below these screws 46. Thus, it is made possible to eliminate all necessity for providing, as in my prior construction, cams which are carried by the casing 30 in the bottom of the cylinder where it is difficult and expensive to form the same during manufacture. It is also made possible to provide these 35 cams on readily accessible surfaces of a ring member which may be much less expensively produced and also may be readily hardened. Also, it will be observed that this ring member may be readily removed to permit access to or removal of other parts, while it can also be replaced in the event of wear at a fraction of the expense necessary to replace the main casing, as in my prior construction. This ring member 44 further cooperates in 40 providing an effective oil seal preventing the escape of oil to the threads 17.

In the operation of my improved construction, it will be evident that rotation will normally be transmitted from the turning member 2, herein formed on the extremity of the piston stem 26, to the turning member 3, herein carried by the casing 8, as a result of the engagement of the sloping surfaces 39 on the piston against the cooperating sloping surfaces 42 on the ring 44 fixed to the casing 8. This rotation will be continued 50 so long as the torque does not exceed the predetermined maximum determined by the setting of the oil flow controlling mechanism. When, however, such a maximum is exceeded, the cam surfaces 42, 39 will slip and, the piston portion 24 then moving downward, the pressure will build up in the lower end of the cylinder 10, herein for convenience indicated as the space 48, sufficiently to force up the ball 37 and permit the liquid to 55 flow up through the ports 33, 37a, into the top of the cylinder 10, which herein for convenience is indicated as the space 49. Accordingly, the pressure in the two spaces 48 and 49 will tend to equalize and as a result, the entire piston 11 including the portion 24 and sleeve 21 will tend 60 to move down in such manner as to cause the surfaces 42 and 39 to disengage when the parts are approximately in the position illustrated in 65 Figure 4. When, however, the pressure equalizes in the spaces 48 and 49, the valve 37 will close 70 automatically at substantially the same time that

the cam surfaces 42, 39 pass out of contact with one another angularly. Then, the spring 23 will also act automatically and press the piston 11 toward the cover 9 and this movement of the piston will automatically open the ball valves 29 so that the oil will flow through the ports 28 to bring the ports back into the position shown in Figure 3, wherein the parts of the wrench are again connected ready for use. Obviously, this disconnection and reconnection of the parts will continue so long as the predetermined torque is exceeded, in such manner as to make the wrench inoperative beyond the predetermined pressure limit for which the same is set by the selected adjustment of the spring 36 which may be varied as desired. Further, it will be evident that the parts will be automatically released if too great pressure is applied to the member 2. Also, when the direction of rotation is reversed, a positive drive will be produced by the engagement of the abutments 40 and 43.

In Figure 9, a modified construction is illustrated wherein, instead of a cylindrical spring 23, a conical or telescoping type of spring 50 is provided which is adapted to flatten when compressed. Obviously, the operation of the mechanism equipped with such a spring will be essentially similar to that heretofore described.

While I have herein specifically described two forms which my invention may assume in practice, it will be understood that these forms have been shown for purposes of illustration, and that the invention may be modified and embodied in other forms without departing from its spirit or the scope of the appended claims.

What I claim as new and desire to secure by Letters Patent is:

1. In a fluid controlled torque wrench, cooperating casing and piston elements having turning means thereon and also including a fluid containing cylinder and a plurality of separate piston forming portions engaging in said cylinder, valve means on one of said portions controlling the flow of fluid between opposite sides of said portions, cooperating frictionally engageable drive means on one of said portions and on said casing in one end of said cylinder for transmitting torque between said turning means, and spring means acting between the other of said portions and the opposite end of said cylinder and cooperating with said valve means for maintaining said cooperating means in frictional engagement.

2. In a torque wrench, cooperating casing and piston elements having turning means thereon and also including a cylinder and cooperating separate piston forming portions engaging in said cylinder, one fitting the cylinder walls and the other of smaller diameter, cooperating frictionally engageable drive means on said last mentioned portion and on said casing in one end of said cylinder for transmitting torque between said turning means, and spring means acting between the first mentioned portion and the opposite end of said cylinder for maintaining said cooperating means in frictional engagement.

3. In a torque wrench, cooperating casing and piston elements having turning means thereon and also including a cylinder and a plurality of separate piston forming portions engaging in said cylinder, cooperating frictionally engageable drive means on one of said portions and on said casing in one end of said cylinder for transmitting torque between said turning means, the other of said portions comprising a sleeve of larger

diameter than said first mentioned portion, and spring means acting between said sleeve and the opposite end of said cylinder for maintaining said cooperating means in frictional engagement.

4. In a fluid controlled torque wrench, cooperating casing and piston elements having turning means thereon and also including a fluid containing cylinder and a plurality of separate piston forming portions engaging in said cylinder, valve means on one of said portions controlling the flow of fluid between opposite sides of said portions, cooperating driving lug means on one of said portions and on said casing disposed in one end of said cylinder for transmitting torque between said turning means, spring means acting between the other of said portions and the opposite end of said cylinder and cooperating with said valve means for maintaining said cooperating means in engagement, and means removably mounted in the first mentioned end of said cylinder and carrying the lug means disposed therein.

5. In a torque wrench, cooperating casing and piston elements having turning means thereon and also including a cylinder and a plurality of separate piston forming portions engaging in said cylinder, cooperating driving lug means on one of said portions and on said casing disposed in one end of said cylinder for transmitting torque between said turning means, spring means acting between the other of said portions and the opposite end of said cylinder for maintaining said cooperating means in engagement, and means removably mounted in the first mentioned end of said cylinder and carrying the lug means disposed therein, said first mentioned portion having a piston rod thereon carrying one of said turning means and said lug carrying means comprising a ring through which said rod projects.

6. In a torque wrench, cooperating casing and piston elements including a cylinder and a plurality of separate piston forming portions engaging in said cylinder, cooperating driving lug means on one of said portions and on said casing disposed in one end of said cylinder for transmitting torque between said turning means, and spring means acting between the other of said portions and the opposite end of said cylinder for maintaining said cooperating means in engagement, said lug carrying portion of said piston having a turning member rotatable therewith and projecting through one end of said cylinder and the other end of said cylinder having an axial turning member socket surrounded by said spring means.

7. In a liquid controlled torque wrench, cooperating casing and piston elements including a cylinder and a plurality of engaging piston forming portions in said cylinder for dividing said cylinder into two chambers adapted to contain liquid, cooperating driving lug means on one of said portions and on said casing disposed in one end of said cylinder for transmitting torque between said turning means, valve means on said last mentioned portion controlling the flow of liquid between said chambers, and spring means acting between the other of said portions and the opposite end of said cylinder and cooperating with said valve means for maintaining said cooperating means in engagement, said casing having a cover and said first mentioned piston portion having a rod journaled in said cover and carrying turning means on the projecting end of said rod, and the opposite end of said cylinder having a turning socket therein and an axial

filling aperture in said socket communicating with said cylinder.

8. In a torque wrench, cooperating casing and piston elements having turning means thereon and also including a cylinder and a plurality of engaging piston forming portions in said cylinder, cooperating driving lug means on one of said portions and on said casing disposed in one end of said cylinder for transmitting torque between said turning means, and spring means acting between the other of said portions and the opposite end of said cylinder for maintaining said cooperating means in engagement, said casing having a cover threaded in one end thereof and said first mentioned piston portion having a rod journaled in said cover and said lug means in the first mentioned end of said cylinder being carried on a sealing ring between the cylinder and the cover threads.

9. In a fluid controlled torque wrench, cooperating casing and piston elements having turning means thereon and also including a fluid containing cylinder and a plurality of separate piston forming portions engaging in said cylinder and dividing said cylinder into two fluid containing chambers, cooperating frictionally engageable drive means on one of said portions and on said casing in one end of said cylinder for transmitting torque between said turning means,

spring means acting between the other of said portions and the opposite end of said cylinder and cooperating with said valve means for maintaining said cooperating means in engagement, and valve means carried by said first mentioned portion controlling the flow of fluid to opposite sides of said portion when said frictional drive means slip.

10. In a fluid controlled torque wrench, cooperating casing and piston elements having turning means thereon and also including a fluid containing cylinder and a plurality of separate piston forming portions engaging in said cylinder and dividing said cylinder into two fluid containing chambers, cooperating frictionally engageable drive means on one of said portions and on said casing in one end of said cylinder for transmitting torque between said turning means, spring means acting between the other of said portions and the opposite end of said cylinder and cooperating with said valve means for maintaining said cooperating means in engagement, and valve means carried by said first mentioned portion controlling the flow of fluid to opposite sides of said portion when said frictional drive means slip and including oppositely moving ball valves and cooperating port means controlling the flow to opposite sides of said piston portion.

ERNEST C. WORDEN.
